UNITED STATES PATENT OFFICE.

OLIVER H. CLARK, OF DETROIT, MICHIGAN, ASSIGNOR TO CHRYSLER CORPORATION, OF DETROIT, MICHIGAN, A CORPORATION OF DELAWARE.

DESIGN FOR A COMBINED RADIATOR CASING AND HOOD.

Application filed November 28, 1927. Serial No. 24,316. Term of patent 14 years.

To all whom it may concern:

Be it known that I, OLIVER H. CLARK, a citizen of the United States, residing in the city of Detroit, in the county of Wayne and State of Michigan, have invented a new, original, and ornamental Design for a Combined Radiator Casing and Hood, of which the following is a specification, reference being had to the accompanying drawing, forming a part thereof, in which—

Figure 1 is a perspective view of a radiator casing and hood embodying my design.

Figure 2 is a cross section of the radiator shell.

The characterizing feature shown and intended to be covered comprises a radiator shell which has a relatively thin width in side elevation together with a hood which extends past the point where the radiator filler cap projects upwardly.

I claim:

The ornamental design for a combined radiator casing and hood as shown.

OLIVER H. CLARK.
